UNITED STATES PATENT OFFICE

JAMES N. MACRAE, OF JERSEY CITY, NEW JERSEY, ASSIGNOR TO PETROLEUM HEAT AND POWER COMPANY, OF NEW YORK, N. Y., A CORPORATION OF DELAWARE

VALVE MECHANISM

Application filed July 8, 1927. Serial No. 204,188.

My invention is directed to an improvement in valve mechanism and will be described not by way of limitation, but merely for clarity of description, as valve mechanism adapted for installation in the line between a source of liquid supply and a pump, such as in an oil burner installation for example.

One of the objects of my invention is the provision of a valve construction adapted for installation as above indicated, in which, when the pump taking liquid from the source of supply ceases operation, the system will be sealed against the liquid flowing back to the storage tank or other liquid source.

A further object of my invention is the provision in such valve mechanism of a construction whereby should the suction line be ruptured from any cause siphoning of the liquid through the valve from the storage tank or other source of supply will be prevented.

In the accompanying drawing Fig. 1 shows more or less diagrammatically an oil burner installation with my improved valve mechanism installed therein; and

Fig. 2 shows the valve itself on a larger scale and in part sectional elevation.

Referring to the drawings in detail, 1 designates a source of liquid supply, such as an oil tank or storage tank, while 2 designates an oil burner, it being understood that this burner comprises a pump for drawing fuel from the tank and supplying it to the burner nozzle or atomizer.

3 designates the suction pipe or line through which the liquid, fuel in the present instance, is drawn from the tank 1 by the pump.

In the line 3 intermediate the storage tank 1 and the pump of the burner I provide the anti-siphoning valve 4 of my invention.

As will be seen from Fig. 2, this valve mechanism comprises a body 5 provided with inlet 6 and outlet 7. The body 5 is provided with a screw cap 8.

Intermediate the inlet 6 and outlet 7, the valve body is provided with three inter-communicating chambers 9, 10 and 11, respectively, these chambers gradually increasing

in capacity from the inlet 6 toward the outlet 7.

Within each chamber is mounted a ball valve, these varying in size in accordance with the capacity of the different chambers. 55 I have designated these valves 12, 13 and 14, the valve 12 being mounted in the chamber 9, valve 13 in the chamber 10, and valve 14 in the chamber 11. These valves all seat in the one direction, i. e., toward the inlet 6. 60

Within the cap 8 and resting upon the upper or largest valve 14 is a vertically movable weight 15 cooperating with the valve 14 to seat the same.

Under normal conditions with the pump 65 in operation, the three valves 12, 13 and 14 are unseated due to the action of the pump, so as to permit of the flow of oil or other liquid from the tank or other source of liquid supply 1 through the inlet 6 of the valve body, through the valve chambers and out the outlet 7 to the pump. In oil burner installations, the burner pump may be intermittently operated, and in such an installation as the pump stops, irrespective of the 75 cause, the valves 12, 13 and 14 will automatically seat in the order mentioned, the valve 12 being the first to seat owing to the restricted area in which it works. Each valve seats by gravity, the seating of the 80 valve 14 being augmented by the weight 15. While the valve 12 when seated is fully capable of sealing the system against flowing of the oil or other liquid back to the source of supply 1, the valves 13 and 14 provide an 85 extra safety factor or two for this purpose.

Should a break occur in the suction line between the pump and the outlet 7 of the valve body, the valve 14 and weight 15 are of sufficient mass to seat the valve 14, thereby 90 to prevent any liquid from being siphoned through the valve from the storage tank.

In some types of installation where my valve mechanism is useful, the weight 15 may not be desirable or necessary, and in such installations it is merely necessary to unscrew the cap 8 and remove the weight. In other installations it may be desirable to vary the mass acting upon the valve 14 and in such a case the weight 15 may be substituted by a 100

lighter or a heavier weight as the case may be.

It will be seen, therefore, that I have provided valve mechanism adapted to be inserted between a pump and a source of liquid supply adapted to operate upon cessation of the pumping operation to prevent a flow back to the source of supply of the liquid in the system and to prevent a flow of the liquid in the opposite direction by a siphoning action, should the suction line be ruptured between the pump and valve.

What I claim is:

1. Valve mechanism comprising a valve body provided with an inlet and a suction outlet and with a plurality of aligned intermediate communicating chambers intermediate the inlet and outlet, said chambers varying in area successively, the smallest chamber being adjacent the inlet, the largest adjacent the outlet, a gravity-seated ball valve for each of said chambers, said balls varying in mass directly in accordance with the variation in area of the valve chambers, a cap for said valve body, and a weight within the valve body between the cap and the valve having the greatest mass, said weight cooperating with said valve to facilitate seating of the same.

2. Valve mechanism comprising a valve body having an inlet and an outlet, said valve body being provided interiorly with a plurality of aligned intercommunicating valve chambers, said chambers successively varying in area, with the smallest chamber adjacent the inlet, a ball valve in each chamber, the mass of said valves varying correspondingly to the variation in the area of the valve chamber, with the smallest valve in the smallest chamber, and a cap removably attached to said valve body adjacent the largest valve for permitting of the insertion of a weight within the valve body between said cap and the largest of said valves to facilitate seating of said valve.

45 This specification signed this 6th day of July, 1927.

JAMES N. MACRAE.
